CONCEALED BELT FOR TROUSER SUPPORTS

Nathan Gold, Portland, Oreg.

Application July 29, 1940, Serial No. 348,134

7 Claims. (Cl. 241—8)

This invention relates to a concealed belt for trouser support. The broad idea is not new, though it presents problems that so far have prevented public acceptance. Adequate solution of these problems constitute the objects of the present invention.

An acceptable belt must be adjustable to the human figure, almost infinitely variable.

The belt must rest securely on the hips of the wearer and if he be so fleshy that he has none, visibly, provision must be made, therefor: Trouser support means must be carried by the belt, of such nature that the garment can be supported at the proper height regardless of the band height above the crotch, within limits that may be expected; yet these supports must be yieldable in such manner that they cannot punch the wearer when he stoops over.

Trouser supports must be securely attachable to the belt proper, yet easily detached when the belt is to be washed or dry cleaned, and as easily replaced. They must be interchangeable.

The belt must be so shaped that it will not have any tendency to crawl upward, be it fastened tightly or loosely around the wearer's body. The belt must be soft and yielding yet maintain its full width and not "rope."

These and other objects that will be at once apparent to those skilled in the arts of belt making, tailoring and kindred arts, will be found in the specification and the illustrative drawings which delineate the best form in which I now contemplate achieving the objects stated:

I believe that there is quite considerably more to accomplishing the objects stated than merely a belt with extensible trouser supports in spaced attachment, as has been proposed. In fact there are many things necessary, each of which contributes its necessary function, lacking any of which the belt will lack that much of adequacy as before expressed.

Drawings accompany and form an essential part hereof, in which:

Fig. I and Fig. II are a stretchout of the complete belt, in two figures, the junction lines at the right hand end of Fig. I and the left of Fig. II indicating continuation. Two forms of hip straps are shown, for reasons that will be explained.

Fig. III is a view of the element S, composite trouser support, at enlarged scale for ease in understanding it.

Fig. IV is a section of Fig. III on the line IV—IV, Fig. III.

Fig. V is a section of Fig. IV at V—V, Fig. IV.

Fig. VI is essentially the structure shown in Fig. I but modified by providing a characteristic hip notch in a part of the belt itself, by contouring and providing fastenings front and rear. 5 Whether the joinder of the belt is at the sides or center, I place an elastic insert 31 in the front center. The structure is also modified by the elastic webbing subjacent the hip notch as will be explained.

Fig. VII represents the companion piece or other half of the belt of Fig. VI, the left hand end of Fig. VI and the right hand end of Fig. VII, being the front.

Figs. VIII and IX respectively represent side and front views of the three piece type of belt, Figs. I and II, on the body of a person moderately fleshy.

Fig. X represents the application, back view of the belt of Figs. I and II, to a wearer's body.

Fig. XI represents the front view of trousers put on and being held properly by the belt. It will be noted from this figure that the holder of the trouser support is well at each side of the center of the figure, where it will be covered by a coat, if worn.

Figs. VIII to XI inclusive are pen-and-ink reproductions of photo views of the belt being worn, very carefully made. It will be noted from the last four views, just referred to, that in front 30 the belt is shaped like the well known abdominal belts, though the latter are of necessity much wider unless well stayed. The back view shows the belt drop curved on its upper side and straight over the hips. This drop curved front 35 is important and made possible without tendency of the belt to rope, by the insertion of trouser support, flexible stays, later herein to be described in detail.

In the drawings, 1 is a belt member, preferably made of strong drill, double, or other suitable material. Both halves of the belt will bear the same identifying numeral. 2 is assigned to diagonal pockets set off from the space between the plies by stitching. These pockets are open 40 at the top to receive the composite trouser support element S, to be later described in detail. The fact that the pockets 2 and inserted elements S are diagonally placed is of major importance, as will appear.

Each belt, whether fastened at the sides, or front and rear, will be fashioned with a hip notch 4 that fits down over the hips, when the same are apparent, and as they tend to disappear altogether as is the case with heavily fleshy wearers, I still use the hip notch 4 as before but place an

elastic webbing 5 below and bridging the notch as shown in Figs. VI and VII; then the belt can be drawn tight enough to hold securely and the elastic webbing 5, yieldably distributes a part of the stress so the belt is comfortable.

It will be noted from all figures, especially I and II where it is plainly shown, that there are two lines of snap fasteners such as 6 and that the line of stress they are capable of applying is close to the top of the belt.

According to the wearer's figure, the top strap 8 may be set on fasteners not in alignment with those used for the lower strap 9, referring to the modification shown in Fig. II; hence we have a belt that will stay where it is placed under a wide variety of conditions.

In order of importance in the belt structure, ranking next to the hip notch, is the diagonally placed trouser support member S and its placement.

Referring in Figs. III and IV, the former is cut away as to the fabric of the belt member 1 to expose the assembly S in place. The elements of this composite member S are a base member 10 that is held within the pocket 2, which will be made to fit it reasonably close.

It is inserted from the top of the pocket 2, and made rigid with the base member 10 is a clip 11, which extends upwardly to form another clip 11a, two ears being bent over as for the clip 11, though closer together. A friction lever 12 is placed through a notch 11b. The lower part of the base member 10 is a flexible spring that is riveted to the clip 11 at 13. It is important that the pocket 2 and its contained base member 10 be placed substantially as shown in Figs. I, II, VI and VII so that it flexibly supports the down-curving sides of the hip notch 4 as shown in these figures. This is true even when the elastic webbing 5 is used. See Figs. VI and VII. The spring base portion of 10 will be what may be adequately described as clock spring steel and I find that a piece about .012" thick and $\frac{1}{8}$ " wide is about right. This dimension is, however, given as a guide and not as a limitation.

It must be noted that the upper part or mouth of the pocket 2 is made with a slit somewhat like a buttonhole, transversely of its width, see numeral 15, and the upper part of fabric bounding the slit 15, see numeral 16, rests on the top of the clip 11a, being held in place by the upper spring 18, which is placed behind it as shown in Fig. IV. This prevents withdrawal of the lower part or its working out, by, in effect, closing the top of the pocket after the base member is in it; the small piece of fabric, 16, being the closure member. The upper spring 18 is easily locked in place by working the friction lever 12. This is diagrammatic and other types of adjustable holding device may be substituted if desired, though this is deemed good.

At the top of the upper spring 18, I place an approved clamp 20, swingably attached thereto by the rivet 21, which clamp may be made ornamental or plated if desired since a portion of it will often be in sight. The upper spring 18 can be of the same size and strength as the base spring 10 to advantage. No further detailed description of the clamp 20 is thought needed as it is well known.

The elastic button loop 30 is useful for two purposes; viz. to hold the shirt front of the wearer down, especially a dress shirt, and to hold the belt up when it is placed on the body quite loosely.

It will be seen at once that I may use a fabric belt, by virtue of the elements S, a major portion of which is always between the plies of the belt and act as stays to prevent wrinkling or roping; that the placement of these elements S diagonally, allows the wearer of the belt to bend over or exercise himself vigorously as in playing tennis or base-ball without getting punched by an up-standing rigid trouser holder attached to a belt according to prior art; and further, that the placement of these elements S make possible the hip notch 4, the boundary lines of which would promptly curl up without the flexible stays, when the notch as shown would cease to exist.

This construction also allows the shaping of the belt with the curved outlines most effective for the purpose and likewise easiest to wear, because such a belt conforms to a wearer's body when bent around it, as a straight belt can never do. Diagonal insertion of the flexible stays serves to maintain the belt in shape and when made as shown may be worn without presence of the supports being uncomfortably manifest.

The foregoing description is made as clear as possible and I have been at considerable effort to fully illustrate the ways it may be applied and its benefits realized to the fullest measure. However, these detailed descriptions are intended only to bring out the best forms which I contemplate for my invention. Several modifications are shown, but all are deemed necessary for a full disclosure; however, they are not to be considered as fixing the limits of the invention but only as a full disclosure, the scope of the invention to be determined solely by the language of the claims which follow.

I claim:

1. A concealed type trouser supporting belt of the character described comprising a belt member, means incorporated with said belt member to secure a snug coupling thereof around a wearer's body, said means comprising at least two strap members at each coupling point, independent engaging members for said straps, a plurality of springy stay members secured within the belt structure, said stay members having incorporated therewith springy trouser support members that are extensible above the top of the belt, means for relatively locking said stay portion and said trouser support portion together, and trouser clamp means at the termini of said trouser support members.

2. A concealed type trouser supporting belt of the character described comprising a belt member, means incorporated with said belt member to secure a snug coupling thereof around a wearer's body, said means comprising at least two strap members at each coupling point, independent engaging members for said straps, a plurality of springy stay members secured diagonally within the belt structure, said stay members having incorporated therewith springy trouser support members that are extensible above the top of the belt, means for relatively locking said stay portion and said trouser support portion together, and trouser clamp means at the termini of said trouser support members.

3. In a belt of the character described, pockets in said belt, a base member in each pocket, a trouser support member telescopically engageable with each base member and means preventing withdrawal of the base member from the belt while engaged with the trouser support, comprising a cross slit in one wall of each pocket adjacent its top through which said support

member is thrust, whereby a narrow piece of fabric held at both ends closes the pocket with respect to the base member.

4. In a belt of the character described, pockets in said belt, base members in said pockets, trouser support members telescopically engageable with said base members and means comprising a part of the substance of the belt engageable mutually by the base members and the trouser support members when the same are engaged, effective to prevent withdrawal of said base members from the belt, but non-interferent with adjustability of said support members.

5. In a belt of the character described, having hip notches on opposite sides thereof, a down-curving front portion, diagonal pockets incorporated with said belt of such length as to substantially encompass its width and positioned near the hip notches, spring base members in said pockets, extensible flexible trouser support members telescopically engageable with said spring base members, means for relatively locking the base members and the support members in selective position with respect to each other and means comprising a part of the walls of the

pockets displaceable by inserting the supports in telescopic engagement with the bases, effective to fasten said bases within the pockets.

6. In a trouser supporting belt to be worn underneath the trousers, a belt member provided with hip notches of the character described, diagonal flexible extensible trouser supporters adjacent said hip notches on both sides thereof, diagonal pockets made a part of said belt with 10 in which said supporters are secured to project above the belt, and elastic webbing members substantially closing the hip notches, of such character that they yield to make the notch partially effective when the belt is worn.

7. In a belt of the character described, means of the character described for staying the belt, hip notches provided to properly rest over a wearer's hips, said hip notches being defined as to their upper boundaries by a pair of separable straps above each notch, and a plurality of interengaging fasteners on each strap independent of the adjacent strap, whereby the effective curvature of the belt over the hips may be varied by the manner of engaging the fasteners.
